[57] CLAIM

The ornamental design for a hand-held exercise device, as
shown and described.

DESCRIPTION

FIG. 1 is a top, front and side perspective of a held-held
exercise device showing my new design;

FIG. 2 is a top, rear and side perspective similar to FIG. 1
but with the exercise device having been rotated ninety
degrees (90°) about its transverse axis;

FIG. 3 is a top plan view thereof;

FIG. 4 is a frontal elevation thereof, the rear elevational view
being identical;

FIG. 5 is a bottom plan view thereof; and,

FIG. 6 is an side elevation thereof, the opposite end elevational
view being identical.
